UNITED STATES PATENT OFFICE

141,380

DESIGN FOR A BILLFOLD

William A. Pence, Adell, Wis., assignor to Euger-Kress Company, West Bend, Wis., a corporation of Wisconsin

Application December 7, 1944, Serial No. 116,761

Term of patent 7 years

(Cl. D87—3)

whom it may concern:

I, William A. Pence, a citizen of the United States, residing at Adell, in the county of Sheboygan and State of Wisconsin, invented a new, original, and ornamental design for a Billfold, of which the following is specification, reference being had to the accompanying drawing, forming part thereof.

the drawing:

I claim:

The ornamental design for a billfold, as shown.

WILLIAM A. PENCE.

CERTIFICATE OF CORRECTION.

Design No. 141,380.

May 29, 1945.

WILLIAM A. PENCE.

It is hereby certified that the name of the assignee in the above
bered patent was erroneously described and specified as "Euger-Kress pany" whereas said name should have been described and specified as - Kress Company--, as shown by the record of assignments in this office that the said Letters Patent should be read with this correction the that the same may conform to the record of the case in the Patent Of Signed and sealed this 9th day of October, A. D. 1945.
